TUBE CLOSURE

Ronald R. Robinson, Morton, Ill., assignor to
Caterpillar Tractor Co., Peoria, Ill., a corpora-
tion of California

Application November 7, 1951, Serial No. 255,283

2 Claims. (Cl. 220—38.5)

1

This invention relates to a closure for an up-standing tube and is particularly adapted for use in connection with the filler spout of an engine crank case.

In an engine operating in an environment in which dust and other abrasive materials are present, one of the principal problems encountered is that of preventing the entry of abrasive material into the engine lubricating system. One of the most troublesome sealing problems occurs at the open end of the filling spout for the engine crank case which is normally closed by a removable cover which permits the addition of lubricating oil. Although these caps are usually dust tight, when they are removed to permit the addition of oil to the crank case, they frequently collect dirt and other foreign material which when the cap is replaced is deposited either directly into the engine crank case or within the filler spout so that subsequent oil additions carry this material into the engine crank case.

It is, therefore, an object of the present invention to provide a cap for an engine crank case filler spout having retaining means which, when the cap is removed to permit oil additions to the crank case, holds the cap in a protected position adjacent the open end of the filler spout. It is another object of this invention to provide a cap for an oil filler spout having sealing means to prevent the accumulation of foreign material on the filler spout adjacent its open end. Other objects and advantages of this invention will be made apparent in the following specification wherein reference is made to the accompanying drawings.

In the drawings:

Fig. 1 is a fragmentary view in vertical central section of a crank case filler spout and cap therefor embodying the present invention, and

Fig. 2 is a view like Fig. 1 in a reduced scale illustrating the position of the cap when it is removed to permit the addition of oil to the engine crank case.

In Fig. 1 of the drawings a part of the crank case of an engine or the like is indicated generally at 10 as having an opening 11 communicating with an upstanding tubular member 12 provided to facilitate the addition of lubricating oil to the engine crank case. The tubular member 12 has a flanged portion 13 with openings for the reception of cap screws 14 securing it to the side of the engine crank case 10. A suitable gasket 15 is provided between the flange and the crank case to provide a fluid and dust tight joint. The upper end of the tubular member is closed

5 by a cup-like cap 16 having a central post 17 which is provided with a threaded portion 18 adjacent its free end. The threaded end of the post is adapted to be received in a threaded opening 19 formed in a cross bar 20 provided adjacent the open end of the tubular member. At its free end 21 the central post 17 has an opening for the reception of one end of a flexible chain-like part 22. At its opposite end the 10 chain 22 carries a semi-spherical retainer 23 having a diameter substantially larger than that of the threaded opening 19 in cross bar 20. The chain and stop are provided to permit removal of the cap from the end of the tubular member and to hold it in a protected position adjacent its 15 open end as shown in Fig. 2.

A resilient seal 24 is carried in a groove formed in the interior of the cap and is adapted to be 20 pressed into sealing engagement with the open end of the tubular member 12 by means of an annular plate 25 carried by the cap. The plate bears against a metal sealing ring 26 and is adapted for relative rotation thereon to prevent 25 scuffing of the plate on the seal 24 upon rotation of the cap. An expandable sealing ring 27 is carried in a suitable groove provided in the exterior of the tubular member 12 and is adapted to engage the interior of the cap 16 adjacent its 30 open end. The sealing ring 27 is provided to prevent the accumulation of foreign material about the outside of the tubular member adjacent its upper end. The open end of the cap is preferably internally beveled as shown in the drawings to facilitate fitting of the cap over the 35 end of the tubular member. The length of the cap is substantially greater than half of its diameter and it therefore maintains a large area clean adjacent the upper end of the tube. Thus when the cap is removed and is suspended by the 40 chain 22 as is illustrated in Fig. 2, the edges of the cap will engage only those parts of the tubular member which have been protected and kept clean. This feature is of particular importance in that it prevents the cap coming in contact 45 with abrasive material which would otherwise accumulate on the tubular member 12 and, when the cap is replaced, be deposited either in the crank case or within the tubular member 12 so that subsequent oil additions would carry it directly into the engine crank case.

I claim:

1. A closure for a substantially upright open ended tubular member comprising a cover member of cylindrical shape having one closed end and 55 adapted to fit over the open end of the tubular

member to shield the upper outer portion thereof from contamination, an axially extending post in the cover threaded at its free end, a cross brace adjacent the upper end of the tubular member with a threaded opening therein to receive said threaded end for securing the cover in place, a flexible element depending from the end of the post and having an enlarged end incapable of passing through the threaded opening so that upon removal of the cover, the enlarged end engages the cross brace and supports the cover for engagement only with the protected end of the tube.

2. A closure for a substantially upright open ended tubular member comprising a cover member of cylindrical shape having one closed end and adapted to fit over the open end of the tubular member, sealing means on the tubular member adjacent the open end of the cover member cooperating with the cover to shield the upper outer portion of the tubular member from contamination, an axially extending post in the cover threaded at its free end, a cross brace adjacent the upper end of the tubular member with a

threaded opening therein to receive said threaded end for securing the cover in place, a flexible element depending from the end of the post and having an enlarged end incapable of passing through the threaded opening so that upon removal of the cover the enlarged end engages the cross brace and supports the cover for engagement only with the protected end of the tube.

RONALD R. ROBINSON.
